INKING MECHANISM FOR PRINTING MACHINES

Sam Newton, Altrincham, and Fred Spence, Sale,
England, assignors to Linotype and Machinery
Limited, London, England, a limited-liability
company of Great Britain

Application October 10, 1931, Serial No. 567,998
In Great Britain October 16, 1930

4 Claims. (Cl. 101—356)

This invention relates to inking mechanism of printing machines, particularly machines in which a flat bed is reciprocated beneath the forme cylinder and forme inking rollers, which latter rotate in respectively opposite directions with reversal of travel of the bed.

More particularly the invention relates to mechanism in which two sets of rollers are employed, of which one set serves to work up the ink intermittently fed thereto from the ink fountain, and the other set applies the ink to the forme, means intermediate the two sets being provided for effecting the transfer of ink from one set to the other.

15 In mechanism of this kind, as usually constructed and operated, the full supply of ink for each impression is delivered in a continuous film to the forme rollers from the distributor rollers during one stroke of the bed, because the reversal 20 in the direction of rotation of the forme rollers prevents any transfer of ink to them during the time that the mutually contacting surfaces of the respective sets of rollers are moving in opposite directions.

25 According to the invention, a more efficient distribution of the ink to the forme rollers and greater uniformity in the film of ink applied by said rollers to the printing surface, are secured by an improved method of operation in which ink 30 is actually transferred from the distributor rollers to the forme rollers during the periods of uniform travel of the bed in both directions, so that one half of the full supply of ink for one impression is delivered to the forme rollers during each stroke of the bed.

In one constructional form of apparatus for carrying out the invention, ink is delivered to the distributor rollers from the ink fountain by a swinging ductor roller, is subsequently transferred to a distributor drum located between the distributor rollers and the forme rollers, and is thereafter transferred from the distributor drum to the forme rollers at two distinct stages. This result is attained by the use of a ductor roller 40 in constant rolling contact with the distributor drum, and alternately brought into contact with two rollers of the forme roller set. The distributor drum may conveniently be of a circumference approximately equal to the length of the forme.

45 In another constructional form of the invention, the distributor drum is rotated in continuous contact with the distributor rollers.

The invention will now be more particularly described by reference to the accompanying 50 diagrammatic drawing, in which:

Figures 1 and 2 are elevations representing respectively the above-mentioned two constructional forms of the invention;

In the constructional arrangement illustrated in Figure 1, the before-mentioned two sets of rollers are identified by the reference letters A, B, of which A is the set which serves to work up the ink intermittently conveyed to it from the ink fountain 1, and B is the set which applies the ink to the forme on the bed 2.

The ink is conveyed to the set A from the ink fountain roller 3 by means of a swinging ductor roller 4 which alternately contacts with said fountain roller 3 and the roller 5. This roller 5 is the first of the set A, which also 70 comprises the last roller 6 and a rider roller 7 contacting with both 5 and 6. Obviously, the set A may comprise more rollers than are here represented.

The ink, well worked up by the rollers 5, 75 6 and 7, is transferred to the distributor drum 8 (whose circumference may conveniently be approximately equal to the length of the forme) by a swinging ductor roller 9 which, while making only intermittent contact with the drum 8, 80 is in constant rolling contact with the so-called last roller 6 and thereby largely assists in the working up of the ink by the set A.

The actual transference of ink to the drum 8 takes place during a period which includes 85 the reversal of the bed at one or each end of the stroke, and at times at which the forme roller set B, is out of operative contact with the set A.

The forme roller set B, in the example under 90 review, comprises four forme rollers 10, 11, 12 and 13 arranged in two pairs 10, 11 and 12, 13, each pair surmounted by its respective vibrator roller 14, 15, which latter are both placed in operative rolling contact through mutually 95 contacting intermediate rider rollers 16, 17 and 18.

The transference of ink from the drum 8, 100 to the set B is effected in two distinct stages. This result is attained by the use of a ductor roller 20 which is in permanent rolling contact with the drum 8, and arranged to make contact alternately with the rollers 14, 16.

The ductor roller 20 is journalled in arms 22 105 (one at each side of the machine) which are free to be swung about the axis of the drum 8, and this swinging movement is so timed and controlled that during one uniform travel of the bed in the direction of the arrow a, the ductor roller 20 is in rolling contact with the roller 14, as indicated in full lines in Figure 1, 110

and during the uniform travel of the bed in the reverse direction, the ductor roller 20, is in rolling contact with the roller 16, as indicated in dotted lines in Figure 1.

5 At a stage intermediate those above particularized, the ductor roller 20 is out of contact with both of the rollers 14, 16 and may be maintained in that intermediate position as and when desired.

10 In the alternative constructional form of the invention illustrated in Figure 2, a more efficient distribution of the ink to the forme roller set B, is ensured by the distributor drum 8 being rotated in continuous contact with the distributor roller set A. This arrangement is shown in Figure 2 in conjunction with a forme inking set B arranged as in Figure 1.

According to this last-mentioned arrangement, the ink intermittently fed to the distributor roller set A from the ink fountain 1 by the ductor roller 4 is continuously worked up by the distributor rollers, the distributor drum 8 and the transfer roller 20 and uniformity of the film of ink transferred to the forme roller set B is more efficiently maintained than is possible where the distributor drum 8 receives ink only intermittently from the distributor rollers.

It is to be noted that with both the arrangements above described the transfer of ink to the forme rollers occupies only short periods of the cycle and allows correspondingly longer periods in which the rolling up of the ink by the distributor rollers can be satisfactorily effected.

35 Having described our invention, we declare that what we claim and desire to secure by Letters Patent is:—

1. In inking mechanism for printing machines, the combination of a set of ink distributor rollers rotating always in the same direction, a set of forme inking rollers rotating alternately in opposite directions, an ink distributor drum rotating always in the same direction and adapted to receive ink from the ink distributor rollers and transfer ink to the forme inking rollers, and a ductor roller in constant rolling contact with the drum, two rollers of the forme inking set being so located that the ductor roller makes contact with them in alter-

50 nately in opposite directions, the ductor roller being so located that it is in rolling contact with the forme inking rollers during the time when the forme inking rollers are not in contact with the ductor roller.

55 2. In inking mechanism for printing machines, the combination of a set of ink distributor rollers rotating always in the same direction, a set of forme inking rollers rotating alternately in opposite directions, an ink distributor drum rotating always in the same direction and adapted to receive ink from the ink distributor rollers and transfer ink to the forme inking rollers, and a ductor roller in constant rolling contact with the drum, two rollers of the forme inking set being so located that the ductor roller makes contact with them in alter-

60 nately in opposite directions, the ductor roller being so located that it is in rolling contact with the forme inking rollers during the time when the forme inking rollers are not in contact with the ductor roller.

65 3. In inking mechanism for printing machines, the combination of a set of ink distributor rollers rotating always in the same direction, a set of forme inking rollers rotating alternately in opposite directions, an ink distributor drum rotating always in the same direction and adapted to receive ink from the ink distributor rollers and transfer ink to the forme inking rollers, and a ductor roller in constant rolling contact with the drum, two rollers of the forme inking set being so located that the ductor roller makes contact with them in alter-

70 nately in opposite directions, the ductor roller being so located that it is in rolling contact with the forme inking rollers during the time when the forme inking rollers are not in contact with the ductor roller.

75 4. In inking mechanism for printing machines, the combination of a set of ink distributor rollers rotating always in the same direction, a set of forme inking rollers rotating alternately in opposite directions, an ink distributor drum rotating always in the same direction and adapted to receive ink from the ink distributor rollers and transfer ink to the forme inking rollers, and a ductor roller in constant rolling contact with the drum, two rollers of the forme inking set being so located that the ductor roller makes contact with them in alter-

80 nately in opposite directions, the ductor roller being so located that it is in rolling contact with the forme inking rollers during the time when the forme inking rollers are not in contact with the ductor roller.

85 5. In inking mechanism for printing machines, the combination of a set of ink distributor rollers rotating always in the same direction, a set of forme inking rollers rotating alternately in opposite directions, an ink distributor drum rotating always in the same direction and adapted to receive ink from the ink distributor rollers and transfer ink to the forme inking rollers, and a ductor roller in constant rolling contact with the drum, two rollers of the forme inking set being so located that the ductor roller makes contact with them in alternation during the rotation of said forme inking roller set in respectively opposite directions.

90 6. In inking mechanism for printing machines, the combination of a set of ink distributor rollers rotating always in the same direction, a set of forme inking rollers rotating alternately in opposite directions, an ink distributor drum rotating always in the same direction and adapted to receive ink from the ink distributor rollers and transfer ink to the forme inking rollers, and a ductor roller in constant rolling contact with the drum, two rollers of the forme inking set being so located that the ductor roller makes contact with them in alternation during the rotation of said forme inking roller set in respectively opposite directions.

95 7. In inking mechanism for printing machines, the combination of a set of ink distributor rollers rotating always in the same direction, a set of forme inking rollers rotating alternately in opposite directions, an ink distributor drum intermediate the set of ink distributor rollers and the set of forme inking rollers rotating always in the same direction, a ductor rollers intermittently contacting with the drum to transfer ink thereto from the ink distributor rollers, and a ductor roller in constant rolling contact with the drum, two rollers of the forme inking set being so located that the last-named ductor roller makes contact with one or other of them conformably with their directions of rotation.

100 8. In inking mechanism for printing machines, the combination of a set of ink distributor rollers rotating always in the same direction, a set of forme inking rollers rotating alternately in opposite directions, an ink distributor drum intermediate the set of ink distributor rollers and the set of forme inking rollers rotating always in the same direction and in constant rolling contact with one roller of the distributor roller set, and a ductor roller in constant rolling contact with the drum, two rollers of the forme inking set being so located that the ductor roller makes contact with one or other of them conformably with their directions of rotation.

9. In inking mechanism for printing machines, the combination of a set of ink distributor rollers rotating always in the same direction, a set of forme inking rollers rotating alternately in opposite directions, an ink distributor drum rotating always in the same direction and adapted to receive ink from the ink distributor rollers and transfer ink to the forme inking rollers, and a ductor roller in constant rolling contact with the drum, two rollers of the forme inking set being so located that the ductor roller makes contact with them in alternately in opposite directions, the ductor roller being so located that it is in rolling contact with the forme inking rollers during the time when the forme inking rollers are not in contact with the ductor roller.

130

10. In inking mechanism for printing machines, the combination of a set of ink distributor rollers rotating always in the same direction, a set of forme inking rollers rotating alternately in opposite directions, an ink distributor drum rotating always in the same direction and adapted to receive ink from the ink distributor rollers and transfer ink to the forme inking rollers, and a ductor roller in constant rolling contact with the drum, two rollers of the forme inking set being so located that the ductor roller makes contact with them in alternately in opposite directions, the ductor roller being so located that it is in rolling contact with the forme inking rollers during the time when the forme inking rollers are not in contact with the ductor roller.

135

11. In inking mechanism for printing machines, the combination of a set of ink distributor rollers rotating always in the same direction, a set of forme inking rollers rotating alternately in opposite directions, an ink distributor drum rotating always in the same direction and adapted to receive ink from the ink distributor rollers and transfer ink to the forme inking rollers, and a ductor roller in constant rolling contact with the drum, two rollers of the forme inking set being so located that the ductor roller makes contact with them in alternately in opposite directions, the ductor roller being so located that it is in rolling contact with the forme inking rollers during the time when the forme inking rollers are not in contact with the ductor roller.

140

12. In inking mechanism for printing machines, the combination of a set of ink distributor rollers rotating always in the same direction, a set of forme inking rollers rotating alternately in opposite directions, an ink distributor drum rotating always in the same direction and adapted to receive ink from the ink distributor rollers and transfer ink to the forme inking rollers, and a ductor roller in constant rolling contact with the drum, two rollers of the forme inking set being so located that the ductor roller makes contact with them in alternately in opposite directions, the ductor roller being so located that it is in rolling contact with the forme inking rollers during the time when the forme inking rollers are not in contact with the ductor roller.

145

13. In inking mechanism for printing machines, the combination of a set of ink distributor rollers rotating always in the same direction, a set of forme inking rollers rotating alternately in opposite directions, an ink distributor drum rotating always in the same direction and adapted to receive ink from the ink distributor rollers and transfer ink to the forme inking rollers, and a ductor roller in constant rolling contact with the drum, two rollers of the forme inking set being so located that the ductor roller makes contact with them in alternately in opposite directions, the ductor roller being so located that it is in rolling contact with the forme inking rollers during the time when the forme inking rollers are not in contact with the ductor roller.

150

14. In inking mechanism for printing machines, the combination of a set of ink distributor rollers rotating always in the same direction, a set of forme inking rollers rotating alternately in opposite directions, an ink distributor drum rotating always in the same direction and adapted to receive ink from the ink distributor rollers and transfer ink to the forme inking rollers, and a ductor roller in constant rolling contact with the drum, two rollers of the forme inking set being so located that the ductor roller makes contact with them in alternately in opposite directions, the ductor roller being so located that it is in rolling contact with the forme inking rollers during the time when the forme inking rollers are not in contact with the ductor roller.
